(57)

CLAIM

The ornamental design for a reload kit for fire extinguisher, as shown and described.

DESCRIPTION

FIG. 1 is a top perspective view.

FIG. 2 is a side plan view; and,

FIG. 3 is a front plan view.

Broken lines in the drawings are included for the purpose of illustrating an environment and form no part of the claimed design. The claimed invention can be used in other environments.

1 Claim, 3 Drawing Sheets**Matter enclosed in heavy brackets [ ] appears in the original patent but forms no part of this reissue; matter printed in italics indicates the additions made by reissue.**(56)
